UNITED STATES PATENT OFFICE.

LEBRECHT STEINMÜLLER, OF GUMMERSBACH, GERMANY.

TRAVELING-GRAVE FURNACE.

Application filed February 11, 1921. Serial No. 444,226.

To all whom it may concern:

Be it known that I, LEBRECHT STEINMÜLLER, a citizen of the German Empire, residing at Gummersbach, Province of the Rhine, Germany, have invented certain new and useful Improvements in Traveling-Grate Furnaces (for which I have filed applications in Germany, April 8, 1919, Patent No. 388,288; France, Oct. 2, 1919, Patent 520,153; 5 Hungary, Sept. 29, 1919, Patent 77,331; Norway, Sept. 24, 1919, Patent 33,995; Belgium, Sept. 27, 1919, 282,476; Switzerland, Sept. 11, 1919, Patent 88,150; Holland, Oct. 25, 1919, Patent 7,328; Great Britain, Sept. 15 25, 1919, Patent 151,470; Italy, Oct. 10, 1919, Patent 178,673; Sweden, Sept. 17, 1919, Patent 54,214; Finland, Oct. 4, 1919, Patent 8,052; Poland, March 3, 1920, application pending; Austria, Sept. 1, 1919, Patent 85, 20 483; Denmark, Sept. 20, 1919, Patent 28,527; Czechoslovakia, Nov. 26, 1919, application pending; Spain, Sept. 29, 1919, Patent No. 70,982), of which this is a specification.

The present invention relates to traveling grate furnaces and particularly to furnaces of this type having a wall or fire bridge overhanging the grate adjacent its rear or discharge end, and having means designed and constructed to prevent the entrance of air into the combustion space through the opening between the grate proper and the lower end of the fire bridge. Means of the character indicated have been heretofore designed or suggested and have 35 consisted usually in a plurality of movably suspended members hung from the fire bridge and having their lower ends in proximity to the upper surface of the bed of fuel and ash lying upon the grate.

40 In application Serial No. 444,227 filed in the names of Max Gensch and myself as joint inventors, is disclosed and claimed a novel means designed and constructed to cause the formation of a bank of fuel substantially within the ash discharge opening of a traveling grate furnace of the type indicated which means comprises a plurality of suspended members individually operable and extending into the body of the fuel on 45 the grate. These members so resist the passage of the fuel and ash through the discharge opening that a considerable fuel bank is maintained in front of said members, which fuel bank, together with the mechanical means for maintaining it, substantially closes the ash discharge opening, and

the resisting means is of such character that any air passing through the ash discharge opening into the combustion space is guided through the bank of fuel. As a result, no free or uncombined oxygen may enter the combustion space through said opening. The apparatus above described has a number of important advantages fully brought out in the specification referred to. 65

The object of the present invention is to provide an improved mechanism of this class provided with means to cooperate with the retarding means to cause the retarding means to exert the desired pressure against the fuel and ash in front of the same to maintain the bank, and to decrease suddenly this resisting or counter pressure when the pressure of the ash becomes excessive because of the presence of a clinker, to quickly release the clinker; and to quickly reapply the original counter pressure to the ash following, after the clinker has passed, so that the bank is maintained along the entire length of the retarding or banking device. 80

The invention may have various embodiments several of which are illustrated in the accompanying drawings and are below described in detail.

In the drawings:

Figure 1 is a transverse section through the retarding device and fire bridge, showing diagrammatically the position of the fire grate;

Figure 2 is a similar view of a modified form of the invention;

Figure 3 is a similar view of a third form of the invention;

Figure 4 is a section on line 4-4 of Figure 3; and

Figure 5 is a transverse section through the furnace combustion space looking toward the fuel retarding members.

As previously pointed out, the mechanism operates in such manner that the fuel retarding member is opened rapidly (when it is necessary for it to open) so that the pieces or lumps of clinker pass rapidly therethrough, whereupon the fuel retarding member closes again rapidly in order to interrupt the fuel retarding action for as short a period as possible.

For this purpose the fuel retarding member is provided with an automatically movable auxiliary weight which is adjustable to vary the closing action of the fuel retarding member. The weight may be adapted to roll

along a track connected to the fuel retarding member, the track constituting in itself a constant weight rigidly secured to the retarding member. The trackway may be independently mounted, if desired, and operatively connected to the retarding member.

Referring to Figure 1, a fuel retarding member is indicated at *a* it being understood that a plurality of such members are utilized, 10 being pivotally hung from a common shaft *b* which is in turn preferably supported upon the lower end of the transversely extending fire bridge *c*, which may be water cooled, if desired. The number of retarding gate 15 members will vary with the width of the grate, as will be understood by those skilled in the art.

To each member *a* is rigidly secured a trackway or lever *d* having a projection *d'* 20 which normally rests on a stop *e* preferably formed of a piece of angle iron. The trackway *d* may be formed in various ways to accommodate or support a rolling weight or ball *f*. It may be a tubular member or channel shaped. The inclination of the trackway *d* is such that, when the member *a* is in its normal position as shown, the rolling weight *f* rests at the outer end of the lever *d* thus exerting greatest turning moment on the 25 member *a* and therefore causing said member to exert the greatest resistance or counter-pressure against the layer of fuel carried forward by the traveling grate *g*. The fuel, which may be finely granulated material, is 30 thus retarded so that it is completely consumed before discharge of the ash. If the pressure of a clinker against the member *a* is so great that the clinker must be discharged, the member *a* will swing back and 35 raise the trackway *d* so that the trackway *d* passes its horizontal position and assumes an opposite inclination to its normal position. During this movement the weight *f* will roll toward the left so that pressure on the member *a* is correspondingly lessened and consequently the member *a* can be easily and rapidly opened further under the pressure of the clinker, so that the member *a* opens 40 sufficiently to discharge the clinker without offering material resistance thereto. As soon as the clinker has passed beneath the member *a* the latter falls until the trackway *d* again passes its horizontal position, when 45 the weight *f* will roll to the right and thus 50 suddenly increase the pressure on the member *a* and therefore accelerate the closing thereof and assist in holding the member *a* in its closed position.

In the modification illustrated in Figure 2, 60 a trackway *d* is employed in the form of a double-armed lever pivotally supported upon the shaft *h*. The trackway is similarly provided with a rolling weight *f*. The member *a* is provided with a roller *k* 65 which engages one arm of the lever *d* and

a pin *l* is provided on the member *a* to limit the downward movement of trackway or lever *d* in a counterclockwise direction and to transmit the weight of this member to the retarding device *a*. Pressure of the 70 clinker against the member *a* thus causes the pin *l* to tilt the trackway *d* from the position shown in full lines in Figure 2, with the weight at its lower end, to the position shown in broken lines in this figure. 75 The forces acting on the retarding member *a* must always be such that in any position of the member *a*, the pressure tends to close this member, in order to insure the closing thereof after the discharge of the clinker. 80

In the modification illustrated in Figures 3 and 4 the double armed lever or trackway *d* is of U-shape and at the front end embraces a roller *z* on the fuel retarding member *a*, being closed at the rear by a cross piece *y*. In the guide so formed is mounted a weight *f* which is preferably constructed as shown in Figure 4.

The normal position is shown in full lines in Figure 3 where the weight *f* is situated at the left hand side of the pivot of the lever or trackway, that is to say, close to and exerting pressure upon the fuel retarding member. When the latter is swung out, as shown in dotted lines, the weight *f* moves to the outer end of the trackway, thus assisting the opening movement of the fuel retarding member.

Mounted upon the pivotal shaft *x* from which the double armed lever is suspended, beyond the end of the grate and outside of the furnace, is a hand wheel *w* by means of which the shaft *x* may be rotated in either direction without directly actuating the trackway *d* mounted loosely on the shaft *x*. Secured upon the shaft *x*, however, is an arm *s* which is moved to the right or left according to the rotation of the shaft *x* through the hand wheel *w*. In the preferred construction, the retarding members *a* are relatively narrow, having in many instances greater length than width, and a sufficient number of these members are suspended side by side from the shaft *b* to extend from one edge of the grate to the other. An individual trackway *d* is provided for each member, and an individual operating arm *s* is provided for each trackway. The invention is not limited, however, to retarding members of any particular width.

In the position illustrated in full lines in Figure 3, the arm *s* rests on the trackway *d* in such position that it increases the pressure of the mechanism against the retarding member *a*. If the shaft *x* is rotated in a clockwise direction, the arm *s* will be moved to the right hand side of the shaft *x* so that the weight of the arm *s* will tend to raise the fuel retarding member. By 130

further rotation of the hand wheel w , the trackway or double-armed lever d^3 may be swung in a clockwise direction, and the fuel retarding member a^2 lifted to inoperative position, as shown in dotted lines. When turned in an anti-clockwise direction the fuel retarding member will be returned from the open position to its normal working position, as shown in full lines. Generally, however, and in the usual operation of the furnace, the hand wheel is turned so that the arm s occupies an intermediate or neutral position and does not affect the operation of the weight mechanism.

To one skilled in the art the advantages of the invention will be apparent and it will also be obvious that additional modifications and variations of form may be employed without departing from the spirit and scope of the invention.

Having thus described the invention what is claimed as new and desired to be secured by Letters Patent is:

1. In a traveling grate furnace, the combination of the traveling grate with a wall or fire bridge overhanging the same and adjacent the discharge end thereof, the lower end of the bridge being spaced above the grate to provide ample opening for the passage of ashes and clinkers, and means for maintaining a bank of fuel and ash on the grate, which means, together with the fuel bank substantially closes the said opening against the ingress of free oxygen into the combustion space and second means acting on said first means to cause the same to resist the passage of ash toward the discharge end of the grate with a variable force, the resisting force decreasing suddenly when said first means is moved by the ash to a predetermined point and increasing suddenly when said means reaches said predetermined point in its return movement, whereby clinkers of relatively large size may be quickly discharged, and maximum pressure on the ash following the clinker quickly reapplied.

2. In a traveling grate furnace, the combination of the traveling grate and a fire bridge above the same adjacent its discharge end, the lower edge of the bridge being spaced above the grate to provide ample opening for the passage of clinkers, and means for maintaining a bank of fuel on the grate adjacent said wall, said means including a plurality of aligned swinging gate members, and said means, together with the bank of fuel substantially closing said opening against the ingress of free oxygen into the combustion space, and means connected to each gate member and designed and constructed to cause said gate member to resist the passage of ashes with a variable force, said last mentioned means including a trackway mov-

ably supported independently of said gate member but connected thereto, and a weight movable along said trackway, said weight moving along the trackway in one direction when the gate member passes a predetermined point in its opening movement, to decrease the pressure of the gate against the ash, and moving along this trackway in the opposite direction when the gate passes this point on its closing movement, to increase suddenly the pressure of the gate against the ash.

3. In a traveling grate furnace, the combination of the traveling grate and a fire bridge above the same adjacent its discharge end, the lower edge of the bridge being spaced above the grate to provide ample opening for the passage of clinkers, and means for maintaining a bank of fuel on the grate adjacent said wall, said means including a plurality of aligned swinging gate members, which means, together with the bank of fuel substantially closes said opening against the ingress of free oxygen into the combustion space, and second means connected to each gate member to cause the same to resist the passage of ashes with a variable force, said second means including a trackway pivotally supported independently of said gate member and pivotally connected thereto, and a weight movable along said trackway under the influence of gravity, said weight moving along the trackway in one direction when the gate member passes a predetermined point in its opening movement, to decrease the pressure of the gate member against the ash, and moving along the trackway in the opposite direction when the gate passes this point in its closing movement, to increase suddenly the pressure of the gate against the ash.

4. In a traveling grate furnace, the combination of the traveling grate, and a fire bridge above the same adjacent its discharge end, the lower edge of the bridge being spaced above the grate to provide ample opening for the passage of clinkers, of means for maintaining a bank of fuel on the grate adjacent said wall, said means including a plurality of aligned and relatively movable suspended gate members, which means, together with the bank of fuel substantially closes the said opening against the ingress of free oxygen into the combustion space, gravity actuated means connected to each gate member and designed and constructed to cause said gate member to resist the passage of ashes with a variable force, and manually operable means for simultaneously moving all of said gate members either to closed or opened position.

In testimony whereof I affix my signature.

LEBRECHT STEINMÜLLER.
